UNITED STATES PATENT OFFICE.

ERNEST L. VON RAHR, OF HAVERHILL, MASSACHUSETTS.

STEERING-WHEEL.

1,325,341.

Specification of Letters Patent. Patented Dec. 16, 1919.

Application filed June 18, 1919. Serial No. 304,999.

To all whom it may concern:

Be it known that I, ERNEST L. VON RAHR, a citizen of the United States, residing at Haverhill, in the county of Essex and State 5 of Massachusetts, have invented certain new and useful Improvements in Steering-Wheels, of which the following is a specification.

This invention relates to certain new and 10 useful improvements in steering wheels for motor vehicles and the like, and it has for its objects among others to provide a simple and cheap, yet durable and efficient construction of steering wheel applicable to 15 steering posts of the different makes of machines, with means for locking the wheel in place, the construction being such that the same may be unlocked when leaving the car so that the steering wheel will turn 20 freely without turning the wheels of the car should an unauthorized person attempt to drive away with the car.

Heretofore it has been proposed to provide means whereby the steering wheel is 25 locked to the steering post, necessitating a particular construction of post and, hence, the steering wheel is not applicable to different makes of machines.

My improved device is exceedingly simple, of few parts, those readily assembled and not liable to get out of order.

Other objects and advantages of the invention will hereinafter appear and the novel features thereof will be particularly 35 pointed out in the appended claims.

The invention is clearly illustrated in the accompanying drawing, which, with the numerals of reference marked thereon, form a part of this specification, and in which— 40 Figure 1 is a top plan of my improved steering wheel applied to a steering post.

Fig. 2 is a vertical section with a part broken away.

Fig. 3 is an elevation of the central portion or cylinder removed, with the steering wheel in position.

Like numerals of reference indicate like parts throughout the different views.

Referring to the drawings,

50 1 designates the outer or rim portion of the steering wheel which is designed to be grasped by the hands of the driver, and 2 are the radial members connecting the same with the annular member 3.

55 4 is a cylindrical member designed to fit within the annular member 3, having at its

lower edge an annular flange 5 extended beyond the periphery of the member 4 and adapted to bear against the under face of the annular member 3, as shown clearly in Fig. 2. The upper face of the member 4 is provided with an annular flange or shoulder 6, as seen clearly in Figs. 2 and 3, with an annular shoulder 7, as seen best in Fig. 3, and the periphery of the member 4 is provided with an opening 8, as seen in Figs. 2 and 3, which is adapted to receive the bolt 9 of a lock of any suitable nature. This lock is carried in the annular member 3, as seen best in Fig. 2, the barrel 10 thereof being seated in a chamber or the like 11 in said annular member and provided with a key-hole 12 adapted to receive a key 13, in the present instance the same being shown as of the type known as the Yale lock, for an obvious purpose.

The member 4 is provided with a central polygonal opening 14 designed to receive the correspondingly shaped portion 15 of the steering post 16. The upper end of the steering post beyond the polygonal portion may be provided with a cylindrical portion 17 screw-threaded to receive the ornamental cap 18, as seen in Fig. 2, if desired.

19 is a ring fitting in the space formed by the shoulders 6 and 7 and secured to the member 4 by suitable means, as shown at 20, these last-named means being removable for the purpose of disassembling the parts when desired. When in position, the ring serves to hold the parts in assembled position.

If desired, the central member, either the member 4 or the ring 19, may be provided with some indicating character such as an arrow 21, as seen in Fig. 1, to indicate when the parts are in proper position so that the bolt of the lock may be thrown into the opening 8 of the member 4.

In practice, the wheels are made for the market with the center holes for the steering posts made to fit the different makes of machines, so that one can simply buy the steering wheel, place it upon a steering post and no modification or alteration of the latter is necessary. When the car is to be used, the key is turned so as to throw the bolt into locking position, as indicated in Fig. 2, when the wheel operates as usual. When the driver leaves the car, he turns the key so as to throw the bolt out of the opening 8 in the member 4 so that the inner and outer members are disconnected and the

outer portion may be turned completely around without moving the inner portion, and, consequently, no motion is imparted to the wheels and the car cannot be run. When 5 the driver again enters the car, he simply throws the bolt into locked position and the wheel is ready for use.

Modifications in detail may be resorted to without departing from the spirit of the invention or sacrificing any of its advantages.

What is claimed as new is:—

1. A steering wheel applicable to an ordinary steering post and comprising an annular member with a steering rim and a locking member, and a cylindrical member applicable to an ordinary steering post and having a peripheral opening to receive the bolt of the locking member, said cylindrical member having an annular flange against

which the lower edge of said annular member rests, and means secured to the upper face of the cylindrical member and overlapping the annular member.

2. A steering wheel applicable to an ordinary steering post and comprising an annular member with a steering rim and a locking member, a cylindrical member applicable to an ordinary steering post and having a peripheral opening to receive the bolt of the locking member and with a flange at 25 its lower portion and a flange and shoulder at its upper portion, the lower flange adapted to support said annular member, and a ring seated on the upper flange and engaging said shoulder and overlapping the 30 adjacent edge of said annular member.

In testimony whereof I affix my signature,
ERNEST L. VON RAHR.
